(57) CLAIM

The ornamental design for cabinet handle, as shown and described.

DESCRIPTION

FIG. 1 is a perspective view of a first handle;

FIG. 2 is a top view of the handle shown in FIG. 1, the undisclosed bottom is not part of the claimed design;

FIG. 3 is a front view of a handle shown in FIG. 1;

FIG. 4 is a side view of the handle shown in FIG. 1, the opposite side is a mirror image.

The broken lines are included for the purposes of illustration and form no part of the claimed design.
